United States Patent Office

Des. 187,265
Patented Feb. 23, 1960

187,265

CHAIR END STANDARD

Chester J. Barecki, Grand Rapids, Mich., assignor to
American Seating Company, Grand Rapids, Mich., a
corporation of New Jersey

Application August 5, 1959, Serial No. 57,073

Term of patent 14 years

(Cl. D15—8)

Fig. 1

Fig. 2

Fig. 3

Fig. 5

Figure 1 is a side elevational view of a chair end standard embodying my new design;

Figure 2 is a front elevational view thereof;

Figure 3 is a rear elevational view thereof;

Figure 4 is a horizontal sectional view thereof taken on line 4—4 of Figure 1; and

Figure 5 is an enlarged fragmentary horizontal sectional view thereof taken on line 5—5 of Figure 1.

I claim:

The ornamental design for a chair end standard, substantially as shown.
